UNITED STATES PATENT OFFICE

LOUIS J. LAROCHE, OF READING, PENNSYLVANIA

DESIGN FOR AN ASH STAND

Application filed August 30, 1929. Serial No. 32,628. Term of patent 3½ years.

To all whom it may concern:

Be it known that I, LOUIS J. LAROCHE, a citizen of the United States, residing at Reading, in the county of Berks and State of Pennsylvania, have invented a new, original, and ornamental Design for Ash Stands, reference being had to the accompanying drawing, forming a part thereof.

The figure is a perspective view of an ash stand showing my new design.

I claim:—

The ornamental design for an ash stand, as shown.

In testimony whereof I affix my signature.

LOUIS J. LAROCHE.
